UNITED STATES PATENT OFFICE.

ALBERT L. TRABUE, OF MAYS, INDIANA.

STORM-SHIELD AND BUGGY-TOP.

No. 870,859.

Specification of Letters Patent.

Patented Nov. 12, 1907.

Application filed May 20, 1907. Serial No. 374,698.

To all whom it may concern:

Be it known that I, ALBERT L. TRABUE, a citizen of the United States, residing at Mays, in the county of Rush and State of Indiana, have invented a new and 5 useful Storm-Shield and Buggy-Top, of which the following is a specification.

This invention relates to storm fronts for buggies, carriages and other vehicles and has for its object to provide a storm front or shield capable of being readily 10 attached to or detached from the vehicle and which will effectually protect the occupant or occupants of the vehicle from the action of the elements.

A further object of the invention is to provide a storm front or shield having its upper end attached to the vehicle top and its lower end fastened to the front sill of 15 the vehicle bed, said shield being so arranged as to permit free access to and egress from the vehicle.

A further object is to provide the shield with relatively stationary and movable side curtains having 20 terminal interlocking hooks adapted to engage one of the side bows or props of the vehicle for supporting said curtains in closed position.

A further object is to provide means for yieldably supporting the lower end of the movable curtain in contact with the exterior walls of the vehicle body, and 25 means for retaining the upper edge of said curtain in engagement with the interior of the vehicle top thereby to prevent the entrance of rain or snow to the interior of the vehicle.

30 A still further object of the invention is to generally improve this class of devices so as to increase their utility, durability and efficiency.

Further objects and advantages will appear in the following description, it being understood that various 35 changes in form, proportions and minor details of construction may be resorted to within the scope of the appended claims.

In the accompanying drawings forming a part of this specification: Figure 1 is a perspective view of a storm 40 front or shield constructed in accordance with my invention. Fig. 2 is a side elevation partly in section of the same. Fig. 3 is a transverse sectional view. Fig. 4 is a detail longitudinal sectional view showing the manner of supporting the lower edge of the movable curtain 45 in contact with the vehicle body. Fig. 5 is a detail perspective view of the movable front bow or prop of the vehicle top. Fig. 6 is a top plan view of the inner end of the frame supporting brace or arm. Fig. 7 is a transverse sectional view of one end of the movable curtain.

50 Similar numerals of reference indicate corresponding parts in all of the figures of the drawings.

The improved shield forming the subject matter of the present invention may be attached to buggies, carriages and other vehicles and by way of illustration is 55 shown applied to a buggy of the ordinary construction

in which 5 designates the body of the vehicle, 6 the folding top, and 7, 8 and 9 the side bows.

The storm shield or front consists of a substantially rectangular frame preferably formed of angle iron and having its lower end bolted or otherwise detachably 60 secured to the front sill 10 of the vehicle bed, said frame being covered with a strip of water proof material 11 so as to form a closure for the front portion of the vehicle.

Secured to the top of the frame 12 is a laterally extending hood 13 which over-laps the adjacent edge of 65 the vehicle top 6 and is provided with oppositely disposed attaching strips 14 adapted to engage suitable braces or arms 15 extending laterally from the longitudinal side bars 16 of the frame 12 so that by adjusting said straps the hoods 13 may be drawn tightly over the 70 upper surface of the top 6 and thus form a water tight joint between the two.

The front bow 7 is detachably secured to the vehicle top and is provided at one end thereof with a reduced threaded extension 17 adapted to engage a correspondingly threaded socket 18 formed in the adjacent top bow 19 of the vehicle top, the opposite end of the bow 7 being detachably secured to the juncture plate 20 by means of a screw or similar clamping device 21.

It will thus be seen that by releasing the clamping 80 screw 21 and rotating the front bow 7, the latter may be readily detached from the top bow 19 so as to permit free access to or egress from the interior of the vehicle when the storm shield or front is attached thereto.

The braces 15 are riveted or otherwise rigidly secured 85 to the longitudinal side bars, as indicated at 22, and are provided with off-set portions 23 having openings 24 formed therein and adapted to register with the sockets 18 in the top bow 19 when the side bow 7 is removed, the free end of the brace 15 being extended rearwardly 90 in parallel relation to the lower edge of the vehicle top and provided with a terminal hook or clamping member 25 adapted to engage the central side bow 8 of the vehicle top, as best shown in Fig. 2 of the drawings. It will thus be seen that the arms 15 by engagement 95 with the top bow 19 and side bow 8 serve to reinforce and strengthen the front portion of the vehicle when the front bow 7 is removed as well as to assist in retaining the storm shield or front in position on the vehicle.

The braces or arms 15 are secured to the top bow 19 100 by means of screws or similar fastening devices 26 while the loops or clamps 25 are provided with suitable fastening devices 27 for clamping the loops in engagement with the side bows.

Pivotedly mounted for swinging movement on the 105 frame 12 is a window or closure 28 having a transparent plate 29 adapted to be swung upwardly on the pivot point 30 to the dotted line position indicated in Fig. 2 of the drawings, said window or closure being secured in elevated or inoperative position by means of a strap 110

or similar suspension device 31 depending from the center bow 32 of the vehicle top.

Arranged on opposite sides of the frame 12 and housed by the longitudinal angle bars 16 are spring actuated 5 rollers 33, each provided with a flexible curtain 34 adapted to form a closure for the adjacent side of the vehicle so as to prevent the entrance of rain or snow in inclement weather.

Secured to the free edges of the movable curtain 34 10 are vertically disposed metal plates 35 having their free ends bent laterally to form terminal hooks 36 adapted to engage the center bow or prop 8 thereby to lock the curtain in closed or operative position.

The hooks 36 are preferably lined with a strip of felt, 15 rubber or other yieldable material 37 adapted to bear against the bow 8 so as to prevent abraiding, scratching or otherwise injuring the bow..

The upper edge of each curtain 34 extends above the lower edge of the vehicle top 6 and bears against the 20 interior wall of the top while the lower edge of each curtain over-laps the exterior side walls of the vehicle body so as to prevent the rain from beating in at the sides of the carriage.

As a means for yieldably retaining the curtains in 25 engagement with the top and body of the vehicle, respectively, each curtain is provided with a longitudinally disposed spring bar or rod 38 which is preferably embedded or otherwise secured in or to the curtain in spaced relation to the adjacent plate 35.

30 The spring rod 38 extends the entire length of the curtain so as to prevent the upper edge of the curtain from dropping below the lower edge of the top the intermediate portion of the rod being bent inwardly, as indicated at 39, so as to yieldably support the lower edge of 35 the curtain in engagement with the exterior walls of the vehicle body, in the manner before stated.

Secured to the opposite sides of the vehicle top at the rear of the central bow is a relatively stationary curtain 40 having a window 41 formed therein and 40 provided at its free edge with a longitudinal plate 42 bent to form a hook 43 similar in construction to the hook 36 and adapted to engage the center bow 8. It will thus be seen that when the curtains are in closed or operative position the hooks 36 and 43 will embrace 45 the center bow 8 with the bill of each hook interposed between said bow and the adjacent hook so as to effectively prevent accidental displacement of said hooks.

The storm front or shield is preferably formed with line receiving openings 44 and a horizontally disposed 50 bar or rail 45 to assist the occupant or occupants of the vehicle in entering or leaving the latter. Suitable finger pieces 46 are also preferably secured to the movable curtain 34 so that the latter may be conveniently moved to operative or vertical position.

55 When it is desired to attach the storm front or shield to the vehicle the front bow 7 is removed by detaching the screw 21 and revolving the bow 7 until the threaded end thereof is disengaged from the socket 18. The frame 12 is then placed in position on the vehicle with 60 the lower edge thereof in engagement with the front end or sill 10 of the vehicle body and with the hood 13 over-lapping the front end of the vehicle top 6 after which the arms or braces 15 are secured to the top bow

19 by means of the screws 26 and the free ends of said 65 arms secured to the central bow 8 by adjusting the

fastening devices 27. After the parts are thus assembled the straps 14 are adjusted so as to clamp the free edge of the hood 13 in engagement with the vehicle top and the curtains adjusted laterally until the terminal hooks engage the center bow 8 thus forming an 70 effective closure for the vehicle and consequently preventing the entrance of rain or snow to the interior thereof.

In order to leave the vehicle it is merely necessary to detach the hook 36 from the adjacent center bow 8 75 when the tension of the spring roller will automatically wind the movable curtain on the roller so as to permit free exit at either side of the vehicle.

Attention is here called to the fact that when the movable curtains are moved to closed or operative 80 position the deflected end 39 of the spring rod 38 will bear against the adjacent wall of the vehicle body but when the curtain is released the spring rod will assume a vertical position so as to permit the curtain to be readily wound on the spring rollers.

When it is desired to ventilate the vehicle it is merely necessary to swing the window or closure 28 upwardly to the dotted line position shown in Fig. 2 of the drawings and in which position it will be out of the way of the occupants of the vehicle.

It will of course be understood that the storm fronts or shields may be made in different sizes or shapes so as to adapt the same to different sizes and styles of vehicles.

Having thus described the invention what is claimed 95 is:

1. The combination with a vehicle having a folding top including top and side bows, the front side bow being removable and provided with a threaded extension for engagement with a corresponding socket formed in the adjacent top bow, of a storm shield detachably secured to the vehicle and provided with a hood for engagement with the vehicle top, an arm extending laterally from the shield, and a fastening device adapted to pierce the arm and engage the socket in the top bow when the movable side bow is detached.

2. The combination with a vehicle having a folding top including top and side bows, one of the side bows being removable and adapted to engage a socket formed in the adjacent top bow, a storm shield detachably secured to the vehicle and provided with a hood for engagement with the vehicle top, a supporting arm extending laterally from the storm shield and having an opening formed therein and adapted to register with the socket in the top bow when the removable side bow is detached, and a fastening device engaging the opening and socket for securing the shield in position on the vehicle.

3. The combination with a vehicle having a folding top including top and side bows one of the side bows being removable and provided with a reduced extension adapted to engage a socket formed in the adjacent top bow, arms extending laterally from the shield and provided with means for engagement with one of the side bows, said arms being provided with openings adapted to register with the sockets in the top bow when the removable side bow is detached, clamping screws extending through the openings in the arms and engaging the sockets, roller carrying curtains mounted for rotation on the frame, and attaching straps carried by the opposite ends of the hood and adapted to engage the arms for clamping the hood 125 in engagement with the vehicle top.

In testimony that I claim the foregoing as my own, I have hereto affixed my signature in the presence of two witnesses.

BERT L. TRABUE.
